MOTOR OPERATED WRENCH HAVING
GEAR TRANSMISSION

Walter R. Kahle and Edward R. Johnson, Cincinnati, Ohio, assignors to The Morris Machine Tool Company, Cincinnati, Ohio, a corporation of Ohio

Application August 25, 1948, Serial No. 46,142

10 Claims. (Cl. 81—57)

1

This invention relates to a power wrench, and more particularly relates to a power-driven wrench adapted for attaching a work piece to a work-holding turret, and to a control mechanism for a power wrench.

An object of this invention is to provide a power wrench having a single control handle which can be used to advance a wrench head into operative position, and which can be used to actuate switches for controlling rotation of the wrench head.

A further object of this invention is to provide a power wrench which may be operated by a handle, which handle may be swung in one direction for advancing and retracting the wrench head, and which may be swung in another direction for operating control switches.

A further object of this invention is to provide a power wrench having control mechanism which automatically is stopped as a nut operated by the wrench reaches the limit of its movement.

A further object of this invention is to provide means in connection with controls of a power wrench, to prevent indexing of a turret while the wrench head is engaged.

The above and other objects are attained by the means described herein and disclosed in the accompanying drawings, in which:

Figure 1 is a side elevational view showing a power wrench constructed in accordance with this invention, the wrench being shown in position for operating work-piece holders on a machine tool, the wrench being shown partly broken away and in section for clarity of detail.

Figure 2 is a sectional view along a line 2—2 in Figure 1, a casing of the power wrench being partly broken away to reveal details of construction.

Figure 3 is a side elevational view of the lower portion of the power wrench illustrated in Figure 1, the wrench being shown partly broken away and in section along a control shaft.

Figure 4 is a sectional view along a line 4—4 in Figure 3.

Figure 5 is a fragmentary sectional view along a line 5—5 in Figure 3.

Figure 6 is a fragmentary sectional view along a line 6—6 in Figure 3.

Figure 7 is a perspective view of a switch cam which forms a part of the device.

As illustrated in Figures 1, 2, and 3, the power wrench includes an electric motor 10 having a vertical shaft 11. The shaft 11 actuates a worm shaft 12 through lost motion mechanism 13. A worm 14 at the lower end of the worm shaft 12

turns a worm wheel 16. The worm wheel 16 drives an idle gear 17 which, in turn, drives a splined gear 18. The splined gear 18 drives a splined shaft 19, which extends through the axis of the splined gear 18. The shaft 19 rotates with, and can slide axially through, the gear 18. A wrench head 21, splined to an end of the shaft 19, can be moved into engagement with a nut 22 for turning the nut. The splined shaft 19 has a smooth section 23 of reduced diameter about which a block 24 fits (see Figure 5), and the shaft is rotatable within the block 24. A pin 26 projects outwardly from the block 24 and meshes with a dog 27 (Figure 4). The dog 27 in turn is fixed to a transverse operating or control shaft 28. The block 24 and pin 26 may be moved lengthwise of the axis of the splined shaft 19 as the control shaft 28 is turned, and the block 24 bears against a shoulder 29 on the splined shaft, for advancing the splined shaft and the wrench head 21 axially toward the nut 22 (Figure 1). A coil spring 31 serves to retract the splined shaft and the wrench head.

The dog 27 is mounted at an end of the control shaft 28. At the other end of the shaft 28 is a bifurcated head or clevis 32, which embraces (as shown in Figure 3) a switch cam 33. The cam 33 is supported by a pin 34 that passes through opposite clevis jaws. The cam 33 may rock about the pin 34 and also may turn with the shaft 28. A handle 36 is attached to the switch cam 33 by a shaft 37. The cam 33 and handle 36 may be swung with the shaft 28 for advancing and retracting the wrench head 21. In addition, the cam and handle can be swung about the pin 34 for operating a pair of switches 38 and 39. The switches 38 and 39 may actuate appropriate electric circuits (not shown) for driving the motor 10 in forward and reverse directions. Thus, the operator of the device not only can advance the wrench head 21 into engagement with the nut 22, but also can start the motor 10 in either direction by a swinging movement of the handle 36. A third switch 41 is actuated upon rotation of the shaft 28. A lug 42 attached to the shaft 28 may actuate the switch 41 when the wrench head 21 is fully retracted.

The nut 22 operates a work-holder 43 for clamping a work-piece 44 to a rotatable turret 45. As will be understood, the turret 45 may be rotated to advance the work-piece to a plurality of work stations, the work-piece returning to its initial position after work on it has been completed, whereupon the work-piece can be re-moved. The switch 41 may be connected by an

appropriate circuit, not shown) to means for rotating the turret 45. As long as the wrench head 21 and nut 22 are engaged, the means for rotating the turret may be disconnected, so that the turret cannot be rotated while the wrench head 21 and nut 22 are engaged.

The device which has been described in general terms up to this point will now be described in more detail.

The motor 10 (Figure 1) may be a torque type electric motor which may stall under high load when the nut 22 is fully advanced. The motor 10 is supported at the upper end of a hollow main casing 47. Bolts 48, only one of which is shown, hold the motor 10 on the casing 47, with the shaft 11 vertical. The casing 47 is bolted to a housing 49 of a machine tool by bolts 51. Only a portion of the machine tool is shown, for details of construction of the machine tool do not constitute a feature of the present invention.

A dog tooth clutch member 52, which forms a portion of the lost motion mechanism 13, is keyed to the motor shaft 11. A set screw holds the clutch member 52 in place on the motor shaft 11. As shown in Figures 1 and 2, the clutch member 52 includes two downwardly-extending teeth 53. The worm shaft 12 carries a lower clutch member 54, having upwardly extending teeth 56 which can contact the teeth 53. The lower clutch member 54 is keyed to the shaft 12. A set screw 57 holds the lower clutch member 54 in place on the shaft 12. When the motor 10 starts, the shaft 11 may rotate for a part of a turn before the teeth 53 and 56 come in contact. A hammer blow is struck by the teeth for turning the shaft 12 and for initially starting and loosening the nut 22.

The clutch members 52 and 54 and the worm shaft 12 turn inside and are rotatably mounted in a cavity 58 inside the casing 47. The shaft 12 is journaled in upper and lower bearings indicated at 59 and 61 respectively. The lower bearing 61 is mounted in a well 62, in the lower portion of the casing 47. The upper bearing 59 is held against a shoulder 63 on the shaft 12 by an annular bracket 64. The bracket 64 in turn is bolted to a shoulder 65 inside the casing 47.

The worm 14 is keyed to the shaft 12. A spacer ring 66 holds the worm 14 in spaced relation above the lower bearing 61. A shoulder 67 on the shaft 14 holds down the worm 14.

As is shown in Figure 2, the worm 14 meshes with the worm wheel 16. The worm wheel 16 is keyed to a short transverse shaft 68 journaled in appropriate bearings 69 and 70. A spur gear 71 is also keyed to the shaft 68. The worm wheel 16 and spur gear 71 revolve together. The spur gear 71 meshes with the idle gear 17 which, in turn, is mounted on a second short transverse shaft 72 appropriately journaled in bearings 73 and 74. The idle gear 17 further meshes with the splined gear 18. The splined gear is journaled in bearings 75 and 76, which bearings not only support the gear 18, but also support the splined shaft 19 for rotation with and movement axially inside of the splined gear 18. The bearings are mounted in appropriate seats in a plate 77 and a housing member 78 which form opposite sides of a housing about the gears. The plate 77 and housing 78 are attached to the casing 47 by screws 79 (Figure 1). An end plate 80 (Figures 2 and 3) attached to the plate 77 and housing 78 by screws 81, covers the splined gear 18 and forms an end closure for the housing about the gears.

The splined shaft 19, as shown in Figures 2 and 5, is splined for about one-half its length. The

rest of its length is smooth and of reduced diameter, as shown at 23. The wrench head 21 is splined to the shaft 19 and is held in place on the shaft by a set-screw 82. The head 21 has outwardly-projecting teeth 83, which can mesh with complementary teeth 84 on the nut 22. The inner end of the wrench head 21 may be frustoconical in shape, as indicated at 86. A guide-plate 87 surrounds the splined shaft. The frustoconical inner end 86 of the wrench head is receivable in a frusto-conical opening 88 in the guide plate 87. The guide plate 87 is attached to the plate 77 by screws 89, and the inner end of the guide plate 87 holds the bearings 75 in place. When the wrench head 21 is fully retracted, the inner end 86 of the wrench head can fit in the opening 88.

The housing 78 surrounds the control shaft 28. A cover plate 91 affords access to the hollow interior of the housing 78. A bore 92 through the cover plate 91 rotatably receives the end 23 of the splined shaft 19. A tensioning nut 93 is threaded on the end of the shaft 19. The spring 31 is held between washers 94 and 96, which bear respectively on the cover plate 91 and the tensioning nut 93. Tension in the spring 31 can be adjusted by advancing the nut 93 along the shaft. A set screw 97 holds the nut 93 in place on the shaft 19.

As already pointed out, the block 24 receives the smooth section 23 of the splined shaft. The shaft can rotate in a bore 98 through the block 24 (Figure 5). The pin 26 is received in a lengthwise slot 99 (Figure 4) in a side of the dog 27. The dog 27 in turn is fastened to the control shaft 28 by a pin 101. As shown in Figure 4, the dog 27 can swing to a position shown in full lines from a position shown in dot-dash lines for advancing the pin 26. As already pointed out, movement of the pin 26 advances the block 24, splined shaft 19, and wrench head 21, to bring the wrench head into engagement with the nut 22 (Figure 1).

The control shaft 28, as shown in Figure 3, is formed in two sections for ease of assembly. An inner section 102 carries the dog 27, while an outer section 103 carries the clevis 32. The sections are joined by a ribbed joint 106, and the sections rotate together. The control shaft 28 is supported in appropriate bushings 107, 108, and 109. The bushings 108 and 109 are carried

in bores in shoulders 112 and 113, that form a part of the housing 78. The outer bushing 107, on the other hand, is supported in a bore in a switch plate 114. The switch plate 114 is attached to the housing 78 by screws 115, as shown in Figure 1. Referring again to Figure 3, collars 116 and 117 attached to the sections of the control shaft 28 by set screws, hold the sections of the shaft in place in the housing 78.

The switch 41 is attached to the housing 78 above the shaft 28 by screws 118. A push-button 119 of the switch 41 extends downwardly from the switch toward the shaft 28. As shown in Figure 6, the lug 42 is threaded in a transverse bore of the shaft 28. An outer end of the lug is rounded and extends outwardly from the shaft 28 into position to contact the button 119 when the shaft 28 is positioned for retracting the wrench head. When the wrench head is fully retracted, the lug 42 depresses the button 119.

The switches 38 and 39 are carried by a switch block 121. The shaft 28 passes through a bore 122 in the switch block. The switch block 121 is attached to the shoulder 112 by screws 123, as shown in Figure 2. As shown in Figure 3, the

switch 38 is attached to the upper side of the switch block, and the switch 39 is attached to the lower side of the switch block. Push-button stems 124 and 126 of the switches 38 and 39 respectively, extend toward the switch cam 33.

The push-buttons 124 and 126 can be depressed by upper and lower plungers 127 and 128 respectively. The plungers 127 and 128 can be pushed inwardly as the switch cam 33 is swung about the pin 34. Each plunger moves in a bore in the switch plate 114. Coil springs 129 and 130 abut the stems 124 and 126 and serve to hold the plungers resiliently away from the switches 38 and 39 when not depressed by the switch cam 33.

The switch cam 33 is held normally in a neutral position by a flat-headed plunger 131. The plunger 131 can move in a well in the shaft 28 between the jaws of the clevis 32. A coil spring 132 urges the flat head of the plunger 131 against an inner face 133 of the switch cam 33, to hold the cam in the neutral position.

As shown in Figures 3 and 7, the inner face 133 of the switch cam is flat except for a cut-away portion 134 in a lower corner. As shown in Figure 3, a collar 135 about the clevis 32 limits the distance the switch cam can swing about the pin 34. When the handle 36 is pushed inwardly to a position shown in dot-dash lines in Figure 3, the upper switch 38 is actuated. The upper switch 38 may control operation of the motor during tightening of the nut 22. The lower switch 39, on the other hand, may control operation of the motor during loosening of the nut. When the nut is to be loosened, the handle 36 may be pulled outwardly and moves from the position shown in full lines in Figure 1 toward the outer position shown in dot-dash lines. As the handle advances, the plunger 128 follows the cam-surface 134, and the switch 39 is disconnected to stop the motor 10 when the nut is sufficiently loosened.

As shown in Figure 1, the turret 45 carries a plurality of work-holders with associated operating nuts. The turret may be in the form of a large disc with work-holders mounted around the peripheral edge. Each work-holder can be indexed, in turn, to each of a series of work stations at which machining of the work piece may take place. The work holder 43 is shown at the station at which work pieces are introduced into and removed from the machine. This type of turret and work-holder is known. In Figure 1, three of the work holders are shown, all work holders being of similar construction, similar parts of the second and third work holding device being given the same numbers as parts of the work holder 43, with the addition of the letter "A" after the numeral for parts of the second work-holder, and the letter "B" after the numeral for parts of the third work-holder. Details of construction of the work-holders are best shown in connection with the second work-holder, which is indicated at 43-A. The work-holder 43-A is of Y-shape, having a pair of jaws 135-A, which may engage and hold a disc-shaped work piece 44A. A lower end 136-A of the work-holder 43-A is hinged at 137-A to a bracket 138-A. The bracket 138-A in turn is attached to the turret 45 by screws 139-A. The nut 22-A is threaded on a stud 141-A which extends from the turret toward the power wrench. When the nut is turned, it is advanced in or out along the stud to clamp or unclamp the work piece.

The operation of the power wrench will be clear from the fore-going detailed description and from the drawings. The work piece 44 may be placed under the jaws 135 when the nut 22 is in released position. Then the operator of the device may swing the handle 36 toward the work piece, as shown in Figure 1, to bring the wrench-head 21 into engagement with the nut 22. When the wrench head 21 and nut 22 are engaged, the handle 36 can be pushed inwardly toward the wrench, as indicated in Figure 3, to depress the plunger 127 and actuate the switch 38, starting the motor 10. The motor 10 can turn the nut 22 until the nut is fully engaged, whereupon the motor may stall. Then the handle 36 may be released to move to the position shown in dot-dash lines in Figure 1. In this position the lug 42 actuates the switch 41 to permit indexing of the turret 45 for bringing a finished work piece opposite the wrench. Then the handle 36 can be swung to the position shown in full lines in Figure 1 to engage the wrench head 21 and nut 22. The handle is pulled outwardly as shown in Figure 3 to actuate the switch 39. As the nut 22 rides along the stud 141, the handle 36 moves to the right, as shown in Figure 1. The plunger 128 follows the cam-surface 134 of the switch cam 33, releasing the switch 39 and halting the motor when the nut is released. Then the finished work piece may be removed and a new work piece substituted.

Power is transmitted from the motor 10 through the lost-motion device 13, the worm 14 and gears 16, 17, 18, to the splined shaft 19. The shaft 19 can be advanced axially through the center of the gear 18 when the handle 36 is swung toward or away from the turret 45, as shown in Figure 1. As the handle 36 and control shaft 28 are swung to the left (Figures 1 and 2) the dog 27 drives the block 24 against the shoulder 29 for advancing the wrench head 21. When the handle 36 is released, the spring 31 retracts the wrench head 21 and shaft 19.

The lost-motion device 13 gives a hammer blow at the start of the release of the nut for initially freeing the nut. The switch 41 prevents premature indexing of the turret 45 while the wrench head and nut are engaged. If desired, the motor can be put in operation in either direction before the nut and wrench head are fully engaged, to bring the teeth 83 of the wrench head into alignment with the teeth 84 of the nut.

As will be understood, the element-to-be-turned may take various forms and need not be a nut. Many variations of the device are possible, and the invention is not intended to be limited by the foregoing detailed description and the drawings, except as set out in the appended claims.

60 What is claimed is:

1. In a control device for a power wrench having a rotatable and axially advanceable shaft, a head attached to the shaft for engaging an element-to-be-turned, and means for rotating the shaft, the combination of a control shaft manually rotatable through an acute angle arc, means linking the first mentioned shaft with the control shaft for advancing the first mentioned shaft to bring the head into engagement with the element-to-be-turned upon partial rotation of said control shaft, a switch cam mounted on said control shaft to rotate with said control shaft and to swing about an axis at a right angle to said control shaft, a pair of switches selectively operable by said switch cam upon swinging of said

switch cam in opposite directions, and means connected to said switch cam for swinging said switch cam and for imparting partial rotation to said control shaft.

2. In a control device for a power wrench having a rotatable and axially advanceable shaft, a head attached to the shaft for engaging an element-to-be-turned, and means for rotating the shaft, the combination of a control shaft manually rotatable through an acute angle arc, means linking the first-mentioned shaft with the control shaft for advancing the first mentioned shaft to bring the head into engagement with the element-to-be-turned upon partial rotation of said control shaft, a switch cam mounted on said control shaft to rotate with said control shaft and to swing about an axis at a right angle to said control shaft, a pair of switches selectively operable by said switch cam upon swinging of said switch cam in opposite directions, a third switch operable by said control shaft upon partial rotation of said control shaft, and means connected to said switch cam for swinging said switch cam and for imparting partial rotation to said control shaft.

3. In a control device for a power wrench having a rotatable and axially advanceable shaft, a head attached to the shaft for engaging an element-to-be-turned, and means for rotating the shaft, the combination of a control shaft manually rotatable through an acute angle arc, means linking the first mentioned shaft with the control shaft for advancing the first mentioned shaft to bring the head into engagement with the element-to-be-turned upon partial rotation of said control shaft, a switch cam mounted on said control shaft to rotate with said control shaft and to swing about an axis at a right angle to said control shaft, a pair of switches selectively operable by said switch cam upon swinging of said switch cam in opposite directions, means connected to said switch cam for swinging said switch cam and for partially rotating said control shaft, and resilient means for retracting said head and said axially advanceable shaft upon release of said cam-operating means.

4. In a control device for a power wrench having a rotatable and axially advanceable shaft, a head attached to the shaft for engaging an element-to-be-turned, and means for rotating the shaft, the combination of a control shaft manually rotatable through an acute angle arc, means linking the first mentioned shaft with the control shaft for advancing the first mentioned shaft to bring the head into engagement with the element-to-be-turned upon partial rotation of said control shaft, a switch cam mounted on said control shaft to rotate with said control shaft and to swing about an axis at a right angle to said control shaft, a pair of switches selectively operable by said switch cam upon swinging of said switch cam in opposite directions, a third operable by said control shaft upon partial rotation of said control shaft, means connected to said switch cam for swinging said switch cam and for imparting partial rotation to said control shaft, and resilient means for retracting said head and said axially advanceable shaft upon release of said cam operating means, said third switch being actuated when the head is in retracted position.

5. In a control device for a power wrench having a rotatable and axially advanceable shaft, a head attached to the shaft for engaging an element-to-be-turned, and an electric motor for

rotating the shaft, the combination of a control shaft manually rotatable through an acute angle arc, means linking the axially advanceable shaft with the control shaft for advancing the first mentioned shaft to bring the head into engagement with the element-to-be-turned upon partial rotation of said control shaft, a switch cam mounted on said control shaft to rotate with said control shaft and to swing about an axis at a right angle to said control shaft, a pair of switches selectively operable by said switch cam upon swinging of said switch cam in opposite directions, a housing about said control shaft, said switches being attached to said housing, one of said switches actuating the motor during tightening of the element, the second of said switches actuating the motor during loosening of the element, means for releasing the second of said switches when the element is loosened a predetermined amount, and means connected to said switch cam for swinging said switch cam and for imparting partial rotation to said control shaft.

6. In a power wrench, the combination of a rotatable and axially advanceable shaft, means for rotating the shaft, a head attached to the shaft for engaging an element-to-be-turned, a control shaft manually rotatable through an acute angle arc, means linking said control shaft to said first mentioned shaft for axially advancing said first mentioned shaft upon partial rotation of said control shaft, a switch cam mounted on said control shaft to rotate with said control shaft and to swing about an axis at a right angle to said control shaft, a pair of switches selectively operable by said switch cam upon swinging of said switch cam in opposite directions, and means connected to said switch cam for swinging said switch cam and for imparting partial rotation to said control shaft.

7. In a power wrench, the combination of a rotatable and axially advanceable shaft, means for rotating the shaft, a head attached to the shaft for engaging an element-to-be-turned, a control shaft mounted at a right angle to said first mentioned shaft and manually rotatable through an acute angle arc, a dog extending outwardly from said control shaft and linked to said first mentioned shaft for axially advancing said first mentioned shaft upon partial rotation of said control shaft, a switch cam mounted on said control shaft to rotate with said control shaft and to swing about an axis at a right angle to said control shaft, a pair of switches selectively operable by said switch cam upon swinging of said switch cam in opposite directions, and means connected to said switch cam for swinging said switch cam and for imparting partial rotation to said control shaft.

8. In a power wrench, the combination of a rotatable and axially advanceable shaft, an electric motor for rotating the shaft, a head attached to the shaft for engaging an element-to-be-turned, a control shaft mounted at a right angle to said first mentioned shaft and manually rotatable through an acute angle arc, a dog extending outwardly from said control shaft and linked to said first mentioned shaft for axially advancing said first mentioned shaft upon partial rotation of said control shaft, a switch cam mounted on said control shaft to rotate with said control shaft and to swing about an axis at a right angle to said control shaft, a pair of switches selectively operable by said switch cam upon swinging of said switch cam in opposite directions, and means connected to said switch cam for swinging said switch cam and for imparting partial rotation to said control shaft.

9. In a power wrench, the combination of a rotatable and axially advanceable shaft, an electric motor for rotating the shaft, a head attached to the shaft for engaging an element-to-be-turned, a control shaft mounted at a right angle to said first mentioned shaft and manually rotatable through an acute angle arc, a dog extending outwardly from said control shaft and linked to said first mentioned shaft for axially advancing said first mentioned shaft upon partial rotation of said control shaft, a switch cam mounted on said control shaft to rotate with said control shaft and to swing about an axis at a right angle to said control shaft, a pair of switches selectively operable by said switch cam upon swinging of said switch cam in opposite directions, a housing about said control shaft, said switches being attached

to said housing, one of said switches actuating the motor during tightening of the element, the second of said switches actuating the motor during loosening of the element, means for releasing the second of said switches when the element is loosened a predetermined amount, and means connected to said switch cam for swinging said switch cam and for imparting partial rotation to said control shaft.

9. In a power wrench for a machine having an element-to-be-turned positionable for turning by the wrench, the combination of a rotatable and axially advanceable shaft, means for rotating the shaft, a head attached to the shaft for engaging the element-to-be-turned, a control shaft mounted at a right angle to said first mentioned shaft and manually rotatable through an acute angle arc, a dog extending outwardly from said control shaft and linked to said first mentioned shaft for axially advancing said first mentioned shaft upon partial rotation of said control shaft, a switch cam mounted on said control shaft to rotate with said control shaft and to swing about an axis at a right angle to said control shaft, a pair of switches selectively operable by said switch cam upon swinging of said switch cam in opposite directions, a third switch operable by said control shaft upon partial rotation of said control shaft, said first two switches actuating the shaft-rotating means in opposite directions for tightening and loosening the element, means controlled by the third switch for preventing movement of said element out of position for engagement by the head while engaged thereby, and means connected to said switch cam for swinging said switch cam and for imparting partial rotation to said control shaft.

- 5 10. In a control device for a power wrench having a rotatably and axially advanceable shaft, a head attached to the shaft for engaging an element-to-be-turned and means for rotating the shaft, the combination of a control shaft manually oscillatable through an angle of less than a half turn, means linking the first mentioned shaft with the control shaft for advancing the first mentioned shaft to bring the head into engagement with the element-to-be-turned upon oscillation of said control shaft in one direction, a switch cam mounted on said control shaft to oscillate with said control shaft and to swing upon an axis at a right angle to said control shaft, a pair of switches selectively operable by said switch cam upon swinging of said switch cam in opposite directions, and means connected to said switch cam for swinging said switch cam and for oscillating said control shaft.
